MOWER GUARD CONSTRUCTION

William R. Gillette, Maywood, and Arthur L. Warner, Elgin, Ill., assignors to Illinois Iron and Bolt Company, Carpentersville, Ill., a corporation of Illinois

Application May 22, 1935, Serial No. 22,696

2 Claims. (Cl. 56—298)

This invention relates to mower guard construction, and concerns itself primarily with twin guards for providing two cutting operations for each cutting blade or section when moving in each direction, and with provisions for attaching such guards to standard cutter bars; the arrangement being such that the cutting blades or sections will come to rest within one prong of a guard, as is the practice when single guards are used. These increased number of prongs not only increase the cutting capacity, but they also greatly decrease the possibility of stones or the like from lodging therebetween and breaking the cutting blades or sections.

The invention comprises the novel structure and combination of parts hereinafter described and more particularly pointed out and defined in the appended claims.

In the accompanying drawing which illustrates a preferred form of this invention and in which similar reference numerals refer to similar features in the different views:

Figure 1 is a broken plan view of a cutter bar for a mowing machine equipped with cutter guards involving this invention.

Figure 2 is an enlarged view similar to Figure 1 with parts removed.

Figure 3 is an enlarged sectional view taken substantially upon the line III—III of Figure 1, looking in the direction of the arrows.

In order to explain and illustrate the novel characteristics of this invention, there has been shown in the drawing the usual knife back 1 in connection with which is used a complete knife consisting of the required number of cutting blades or sections 2 riveted to the knife back 1. The knife also includes the usual head, not shown. The sections 2 cooperate with guards 4 for performing the cutting operations. In the past, it has been the common practice to use single guards; each guard being attached by a bolt 5 extending through an aperture 6 in a cutter bar 7, commonly called a naked cutter or finger bar. According to this invention, instead of a single guard, twin guards 4 are employed and they are made integral with a plate 8, usually termed the cutter bar seat having an aperture 9 that is offset from the transverse center line of the cutter bar seat 8 so as to register with the aperture 6 existing in the cutter bar 7 as shown in Fig. 3.

Upon the right hand end of the cutter bar, there is a complete guard 8a having three guard prongs 4 thereon to complete the required number. Each guard plate is attached to the plate

7 by means of a removable bolt 5, whereby the guards may be readily removed.

The guards 4 are shown as provided with a guideway 10 for receiving the knife back 1. At suitable intervals, pressure clips 11, commonly called knife clips may be attached to the naked cutter bar 7 by the bolts 5 for bearing against the cutter blades 2. Suitable spacing plates, commonly called wear plates 12 are preferably placed under the attached portions of the clips 11. The inner ends of the plates 12 have downwardly directed flanges 13 that contact the near side of the knife back and form a part of the guideway 10.

The guards are preferably made from malleable castings that involve a substantial economy over forged guards. The guards are also provided with the usual ledger plates 14 which in the present instance are made of hardened steel so as to more effectively retain their cutting edges. It will be noted that the guard seats 8 have straight side edges 8b which extend to the rear thereof whereby adjacent guard seats are in abutting relation at the bolt apertures 9. As the bolt apertures 9 are in eccentric relation to the center line thereof there is a considerable turning or torsional movement with respect to the securing bolts 5. However since the guard seats are in abutting relation at their rear ends adjacent the securing bolts 5, this turning movement is resisted and overcome.

These twin and triple guards greatly increase the cutting capacity of the complete cutter bars. In offsetting the bolt holes in these guards as above set forth, it is possible to attach the same to standard cutter bars with all the fittings and bring the guards in the proper positions so that the cutter of each knife will momentarily come to rest at the center of a prong of a guard at the extreme outward and inward thrust of the knives and prevent clogging. With the provision of the complete guard with three prongs at one end of the naked cutter bar, and a twin guard at the other end thereof that may be provided with the proper contour to meet the exigency of the shoes on any cutter bar, the problem of providing cutter bars with these twin and triple guards to greatly increase the cutting capacity thereof and at the same time prevent clogging becomes a simple problem.

It will be appreciated that according to this invention, it is possible to remove the guards having a single prong on a cutter bar now in use and replace the same with a guard having a plurality of prongs thereon in order to increase

the cutting action of the sections during the reciprocation thereof. This replacement is effected by using the bolt holes already existing in the naked cutter bar 7 and without drilling any new or additional ones. With this arrangement, one of the prongs on a guard will always occupy the position of the removed guard with the single prong and receive a section when the complete knife is at its extreme outward or inward thrust, 10 since a prong on each complete guard 8 or 8a is in alignment with the aperture 9 therein.

We are aware that many changes may be made and numerous details of construction may be varied through a wide range without departing from the principles of this invention, and we, therefore, do not purpose limiting the patent granted hereon otherwise than is necessitated by the prior art.

We claim as our invention:

20 1. In a mower guard construction, a finger bar having a series of apertures, a plurality of prong seats, each having a pair of prongs with an

aperture offset from the center line thereof and in alignment with a prong, said prong seats having straight side edges in abutting relation at said apertures, bolts extending through said offset apertures and through the apertures in said finger bar for attaching said seats to said bar, the abutting relation of said seats resisting the turning movement of said seats upon said bolts.

2. In a mower guard construction, a finger bar having a series of apertures, a plurality of guard seats, each having a pair of prongs and bolt aperture in alignment with one prong and offset from the center line thereof, said seats having their side edges in abutting relation rearwardly of said apertures, and bolts extending through the apertures in said seats and finger bar for attaching the same together, the abutting relation of said seats resisting the turning movement of said seats about said bolts.
